1 Claim. (Cl. 317—140)

The invention relates to a method of registering pulses by means of a counting relay circuit-arrangement.

Relay circuit-arrangements are already known in which a number of pulses supplied to the counting circuit can be registered in the form of a combination of energized conditions of counting relays, the combination being characteristic of this number. Such counting circuits are used inter alia in registers of automatic telephone systems for the temporary recording of the dial pulses emitted by a subscriber and for the re-emission of an equal number of pulses or a number of pulses derived therefrom. Such circuit-arrangements are furthermore used for marking the outlets of selectors in systems comprising a common control-device or for producing other numerical criteria, for example direct voltages, the value of which is characteristic of the number of incoming pulses.

In the known circuit-arrangements, as a rule, the pulses are registered in the binary system, i. e. a first relay registers the number of units, a second relay the number of doubles, a third relay the number of quadruplets of the incoming digit. However, this method requires a comparatively high number of relays, since these circuit-arrangements are such that, with doubling of the number of pulses that must be registerable at the most, the number of relays must be raised by two, so that the registration of 2^n pulses requires 2^n pulses relays. A further circuit-arrangement is known which permits of registering a maximum number of 2^n pulses by means of n relays. However, the operation of this circuit-arrangement is not very reliable under any circumstances. This circuit-arrangement has a limitation in that magnetizing or demagnetizing of a relay must be carried out through discharge of a capacitor.

The invention is based on the recognition that 2^n different energizing conditions can be distinguished with the use of n relays, since each relay may be in one of two conditions, i. e. energized and not energized. Each pulse requires two conditions, since at the beginning and at the end of each pulse a variation in condition is required for the circuit to be insensitive for the duration of a pulse. In this case a maximum of 2^{n-1} pulses can be counted with the use of n relays. Consequently the registration of 16 pulses requires 5 relays.

In the method according to the invention the circuit comprises n counting relays, in which n is equal to 3 or more. The method is characterized in that the order of succession in which the relays are energized is such (starting from the condition in which all relays are idle) that a relay having the ordinal numeral 1 is energized from the beginning of each odd-numbered pulse till the beginning of each even-numbered pulse and that a relay having the ordinal numeral p (where p is different from 1 and n) is energized at the end of the 2^{p-2} pulse and changes its energizing condition at the end of each 2^{p-1} pulse and that the relay having the ordinal numeral n is energized at the end of the 2^{n-2} pulse and changes its energizing condition after each 2^{n-2} pulse or else that

2

the series of energizing conditions is followed in the negative sense.

The method is such that all practicable energizing conditions of the relays occur in succession, while the energizing condition of only one relay changes at the beginning and at the end of each pulse. This implies that in addition to the counting relay proper, the energizing condition of which gives an indication about the number of incoming pulses, no auxiliary relays are required, as is the case in known counting circuits.

If at the beginning or at the end of a pulse two or more relays would change their conditions, these changes will not take place exactly simultaneously in practice and, so that it is not certain which relay will change its condition first which will create a situation of uncertainty. If one relay changes faster or sooner than the other, a condition is passed in which the energizing condition of the relays corresponds to a particular number of pulses not equal to the real number of incoming pulses. Therefore, the known circuit-arrangements comprise auxiliary relays which bridge the conditions of uncertainty. By the method according to the invention the number of relays can be reduced to a minimum.

A circuit-arrangement which is particularly suitable for carrying out this method is such that a terminal of a supply source is connected through a first contact of the pulse number, by means of which pulses may be fed to the circuit, to a first circuit of series-connected break-contacts of the relays, with the exception of one, the 25 next of the break contacts in this circuit determining the order of succession, one end of a first winding of the first relay of the order of succession being connected through a second contact of a pulse member, this contact switching in a sense opposite to that of the first contact, to the said terminal of the supply source, while one end of a first winding of the further relays are connected each through a make contact of the preceding relay in the order of succession to the side of the break contact of this relay in the first circuit which is remote from the pulse member, the other end of the first winding of the first relay being connected to an inlet of a second circuit, in which in the given order break contacts of the second and the next following relays are included in series and furthermore connected through a make contact of a second relay to the inlet of a third circuit, 35 in which in the given order break contacts of the third and the next following relays are included in series, the ends of the break contacts of each relay included in the second and the third circuit are connected crosswise through make contacts of the associated relays, the other 40 ends of the first windings of the second relay and the next following relay being connected to the end of the break contact of the corresponding relay in the second circuit, which ends are remote from the inlet of the second circuit, the ends of the second and the third circuits remote 45 from the inlet being connected to relatively different terminals of the supply source, each energized relay completing a holding circuit for itself through its own make contact.

60 The term "contact of a relay" is to be understood to mean an electric dipole, with which, under the control of the relay, a connection is established or interrupted between the terminals with a break contact a connection is established between the terminals of a relay in the position of rest, this connection being interrupted when the relay is energized. Conversely, the term "make contact" is understood to mean a contact of which the terminals of the relay are interconnected only when the relay is energized. In view of the operation of the circuit-arrangement it is immaterial to which terminal the moving 65 part of the contact member is connected.

An important advantage of the circuit-arrangement is

that it may be arranged in a simple manner to be such that pulses can be registered both in an additive and in a subtractive sense. This is particularly of importance, if it is required to re-emit a number of pulses equal to the number of incoming pulses. In this case, after the pulses to be registered are recorded, the circuit is moved into a condition in which it can count back, after which pulses, which may, for example, be taken from a standard pulse generator, are supplied to the circuit until a particular initial condition, for example, the condition in which all the relays are at rest, is reached. The circuit-arrangement may be extended without drastic modifications by adding one or more relays.

In order that the invention may be more clearly understood and readily carried into effect, it will now be described more fully with reference to the accompanying drawing.

In the drawing:

Fig. 1 is a graph illustrative of the operation of pulse registering apparatus in accordance with the invention; and

Fig. 2 is a schematic circuit diagram of a preferred embodiment of a pulse registering apparatus in accordance with the invention.

Fig. 1 illustrates the order of succession in which the relays are energized in the method according to the invention. The pulses supplied are indicated at *Imp.* Figs. 1a, 1b and 1c relate to counting circuits comprising 3, 4 and 5 relays respectively. With each circuit the series of energized conditions may, in principle, occur both from the left to the right and in the inverse direction, one direction corresponding, for example, to the registration in an additive sense, the other to the registration in a subtractive sense.

If the series is followed from the left to the right, the first relay is energized from the beginning of an odd-numbered pulse till the beginning of the next following even-numbered pulse. The second relay is energized from the end of the first pulse till the end of the third pulse, from the end of the fifth pulse till the end of the seventh pulse, and so forth. The variations of the energized conditions of the third relay are not equal in the circuit comprising three relays to those in the circuits comprising four or more relays. In the circuit comprising three relays the third relay is energized from the end of the second pulse till the end of the fourth pulse, from the end of the sixth pulse till the end of the eighth pulse, and so forth, if the cycle is followed from the left to the right and the cycle is repeated after series of four pulses. On the contrary, in a circuit comprising four or more relays, the third relay remains energized until the end of the sixth pulse.

In a circuit comprising n relays, the energizing condition of the relays with the exception of the last relay, is in general, symmetrical relative to the end of the 2^{n-1} th pulse. The cycle of the circuit comprising n relays may be derived from that of a circuit comprising $n-1$ relays by reflecting the cycle of each relay of the latter circuit with respect to the end of this cycle. Then the n th relay is energized for the second half of the cycle with n relays. It should be noted that at the beginning and at the end of each pulse only one relay changes its energizing condition.

Fig. 2 shows one embodiment of a circuit comprising 5 relays. This circuit permits of registering 16 pulses. The 5 relays A, B, C, D and E are shown in the figure by their two windings A₁A₂, B₁B₂, C₁C₂, D₁D₂ and E₁E₂. The energizing current for the relays is supplied by a battery *Ba*, of which the positive terminal *P* is grounded. The counting pulses are supplied to the circuit by means of a pulse change-over contact *i* of a relay *R*. The arrangement comprises three circuits K₁, K₂ and K₃ of series-connected break-contacts of the relays. The change-over contacts *a*₁, *b*₁, *c*₁ and *d*₁ of the relays A, B, C and D form a chain circuit, of which the series-

connected break-contacts constitute the circuit K₁. The inlet U₁ thereof is grounded through a break-contact *i* and a break-contact *t*₁ of a relay *T* (not shown). The ends of first windings B₁, C₁, D₁ and E₁ of the relays B, C, D and E are connected to the make-contact of the chain circuit. Between an end of a first winding A₁ of relay A and ground are connected the break-contact *t*₂ of relay *T* and the make-contact *i* of the pulse member. The other end of the winding A₁ is connected to the inlet U₂ of a second circuit K₂. This circuit is constituted by the series-connection of the break-contacts *b*₄, *c*₄, *d*₄ and *e*₄ of the relays B, C, D and E. The other ends of the windings B₁, D₁, C₁ and E₁ are connected to the ends of the break-contacts of the associated relays of this circuit, these ends being remote from the inlet U₂. The other end of the circuit K₂ is connected through the break-contact *t*₃ of relay *T* to the negative terminal N of the battery. The inlet U₂ of the circuit K₂ is connected through the make-contact *b*₄ of relay B to the inlet U₃ of the third circuit K₃, of which the other end is grounded through break-contact *t*₄ of relay *T*. The circuit K₃ is constituted by the series-connection of the break-contacts *c*₅, *d*₅ and *e*₅ of relays C, D and E. The ends of the break-contacts *c*₄ and *c*₅, *d*₄ and *d*₅, *e*₄ and *e*₅ and *t*₃ and *t*₄, associated with the same relay, are connected cross-wise by make-contacts *c*₄ and *c*₅, *d*₄ and *d*₅, *e*₄ and *e*₅, *t*₃ and *t*₄, respectively, of the corresponding relays. The pairs of change-over contacts *c*₄ and *c*₅ and so forth thus form a commutator. The relays are provided with second windings A₂, B₂, C₂, D₂ and E₂ through which, if the relay is energized, in series with its own make-contacts *a*₂ and *a*₃, *b*₂ and *b*₃, *c*₂ and *c*₃, *d*₂ and *d*₃, *e*₂ and *e*₃ and with a resistor R₁, R₂, R₃, R₄, R₅ and R₆ respectively a holding circuit for the relay is completed.

35 The circuit-arrangement operates as follows:

In the position of rest all the relays are deenergized. At the beginning of the first pulse the pulse contact *i* completes an energizing circuit for relay A from ground through contact *i* off, *t*₂ off, winding A₁, contact *b*₄ off, circuit K₂, contact *t*₃ off to battery *Ba*. The term contact *i* up, *t*₂ off is to be understood to mean here the make-contact *i*, the break-contact *t*₂ and so forth. Relay A completes a holding circuit for itself through contact *a*₃ up, its second winding A₂, contact *a*₂ up, resistor R₁.

45 At the end of the first pulse relay B is energized in a circuit from ground through contact *i* off, *t*₁ off, *a*₁ on, winding B₁, contact *c*₄ off, *d*₄ off, *e*₄ off, *t*₃ off to the negative terminal N of the battery. Relay B completes a holding circuit for itself in a manner similar to that 50 of relay A and of the relays to be energized afterwards through a second winding B₂, this holding circuit being here completed through contact *b*₂ up, winding B₂, contact *b*₂ up, resistor R₂. Relay B then changes over the armature of its change-over contact *b*₄, so that at 55 the beginning of the second pulse the winding A₁ of relay A is short-circuited through contact *b*₄ up, *c*₅ off, *d*₅ off, *e*₅ off, *t*₄ off, *i* up and *t*₂ off, while furthermore winding A₂ is short-circuited through contact *a*₃ up, *i* up and *t*₂ off, the relay A falling off. The resistor R₁ here 60 prevents the battery from being short-circuited until make-contact *a*₂ opens.

At the end of the second pulse relay C is energized through contact *i* off, *t*₁ off, *a*₁ off, *b*₁ up, winding C₁, contact *d*₄ off, *e*₄ off and *t*₃ off.

65 At the beginning of the third pulse make-contact *i* completes an energizing circuit for relay A through contact *i* up, *t*₂ off, winding A₁, contact *b*₄ up, *c*₅ up, *d*₄ off, *e*₄ off and *t*₃ off.

70 Relay B is deenergized at the end of the third pulse owing to the short-circuit of winding B₁ through contact *c*₄ up, *d*₅ off, *e*₅ off, *t*₄ off, *i* off, *t*₁ off and *a*₁ up and the winding B₂ through contact *b*₃ up, *i* off, *t*₁ off and *a*₁ up.

At the beginning of the fourth pulse relay A is deenergized owing to the short-circuit of winding A₁ through 75 contact *b*₄ off, *c*₄ up, *d*₅ off, *e*₅ off, *t*₄ off, *i* up and *t*₂ off.

At the end of this pulse relay D is energized through contact i off, t_1 off, a_1 off, b_1 off, c_1 up, winding D_1 , contact e_4 off and t_3 off.

At the beginning of the fifth pulse relay A is energized through contact i up, t_2 off, winding A_1 , contact b_4 off, c_4 up, d_5 up, e_4 off and t_3 off. At the end of this pulse relay B is energized through contact i off, t_1 off, a_1 up, winding B_1 , contact c_4 up, d_5 up, e_4 off, and t_3 off.

Relay A is deenergized at the beginning of the sixth pulse owing to the short-circuit of winding a_1 through contact b_4 up, c_5 up, d_4 up, e_5 off, t_4 off, i up and t_2 off. At the end of this pulse relay C is also deenergized, since its winding C_1 is short-circuited through contact d_4 up, e_5 off, t_4 off, i off, t_1 off, a_1 off and b_1 up the winding C_2 being at the same time short-circuited.

At the beginning of the seventh pulse relay A is again energized through contact i up, t off, winding A_1 , contact b_4 up, c_5 off, d_5 up, e_4 off and t_3 off.

At the end of this pulse relay B is deenergized owing to the short-circuit of its winding B_1 through contact c_4 off, d_4 up, e_5 off, t_4 off, i off, t_1 off and a_1 up and of its winding B_2 .

At the beginning of the eighth pulse relay A is deenergized owing to the short-circuit of its winding A_1 through contact b_4 off, c_4 off, d_4 up, e_5 off, t_4 off, i up and t_2 off and of winding A_2 .

At the end of this pulse relay E is energized through contact i off, t_1 off, a_1 off, b_1 off, c_1 off and d_1 up, winding E_1 and contact t_2 off.

At the beginning of the ninth pulse relay A is energized through contact i up, t_2 off, winding A_1 , contact b_4 off, c_4 off, d_4 up, e_5 up and t_3 off. Relay B is energized at the end of the ninth pulse through contact i off, t_1 off, a_1 up, winding B_1 , contact c_4 off, d_4 up, e_5 up and t_3 off.

At the beginning of the tenth pulse relay A is deenergized owing to the short-circuit of its winding A through contact b_4 up, c_5 off, d_5 up, e_4 up and t_4 off, i up and t_2 off and of winding A_2 .

At the end of the tenth pulse relay C is energized through contact i off, t_1 off, a_1 off, b_1 up, winding C_1 , contact d_4 up and e_5 up and t_3 off.

Relay A is energized at the beginning of the eleventh pulse through contact i up, t_2 off, winding A_1 , contact b_4 up, c_5 up, d_4 up, e_5 up and t_3 off.

At the end of the eleventh pulse winding B_1 is short-circuited through contact c_4 up, d_5 up, e_4 up, t_4 off, i off, and t_1 off, a_1 up, so that relay B is deenergized.

At the beginning of the twelfth pulse winding A_1 is short-circuited through contact b_4 off, c_4 up, d_5 up, e_4 up, t_4 off, i up, t_2 off. At the end of this pulse relay D is deenergized owing to the short-circuit of winding D_1 through contact e_4 up, t_4 off, i off, t_1 off, a_1 off, b_1 off, and c_1 up.

At the beginning of the thirteenth pulse relay A is energized through contact i up, t_2 off, winding A_1 , contact b_4 off, c_2 up, d_5 off, e_5 up and t_3 off. At the end of this pulse relay B is energized through contact i off, t_1 off, a_1 up, winding B_1 , contact c_4 up, d_5 off, e_5 up, t_3 off, i off, t_1 off and a_1 up.

At the beginning of the fourteenth pulse winding A_1 is short-circuited through contact b_4 up, c_5 up, d_4 off, e_4 up, t_4 off, i up and t_2 off. At the end of this pulse winding C_1 of relay C is also short-circuited through contact d_4 off, e_4 up, t_4 off, i off, t_1 off, a_1 off, b_1 up.

At the beginning of the fifteenth pulse relay A is energized through contact i up, t_2 off, winding A_1 , contact b_4 up, c_5 off, d_5 off, e_5 up, and t_3 off. At the end of this pulse winding B_1 is short-circuited through contact c_4 off, d_4 off, e_4 up, t_4 off, i off, t_1 off and a_1 up.

At the beginning of the sixteenth pulse relay A is deenergized owing to the short-circuit of its winding A_2 through contact b_4 off, c_4 off, d_4 off, e_4 up, t_4 off, i up and t_2 off. At the end of this pulse relay E is deenergized as the last relay, since its winding E_2 is short-circuited through contact t_4 off, i off, t_1 off, a_1 off, b_1 off, c_1 off, d_1 off.

The circuit-arrangement may be moved, in a state, from any state into a condition in which pulses are counted back, i. e. the series of energizing conditions is followed in an opposite sense by energizing the relay T so that the commutator contacts t_1 , t_2 , t_3 and t_4 change over.

If, for example, four pulses are received, relays A, B and E are in the position of rest and relays C and D are energized. After relay T has been energized, the pulse member I again supplies pulses to the circuit, this member being, for example, controlled by a standard pulse generator.

At the beginning of the first counting-back pulse relay D is deenergized, since its winding D_1 is short-circuited through contact e_4 off, t_3 up, i up, t_2 up, a_1 off, b_1 off, and c_1 up, winding D_2 being short-circuited through contact d_3 up, i up, t_2 up, a_1 off, b_1 off and c up. At the end of the first pulse relay A is energized through contact i off, t_1 up, winding A_1 , contact b_4 off, c_4 up, d_5 off, e_5 off, and t_4 up.

At the beginning of the second pulse relay B is de-energized through contact i up, t_2 up, a_1 up, winding B_1 , contact c_4 up, d_5 off, e_5 off and t_4 up. At the end of the second pulse relay A is de-energized owing to the short-circuit of its winding A_2 and of its winding A_1 through contact b_4 up, c_5 up, d_4 off and e_4 off, t_3 up, i up, and t_1 up.

At the beginning of the third pulse relay C is de-energized, at the end of the third pulse relay A is energized, at the beginning of the fourth pulse relay B is de-energized and at the end of this pulse relay A is also de-energized, so that all the relays have been deenergized and the circuit-arrangement again takes up its position of rest.

The circuit-arrangement may be modified in various ways within the scope of the invention. In the circuit-arrangement described, a relay is demagnetized for short-circuiting its windings. As a matter of course, a relay may, as an alternative be deenergized by counter-magnetization through the main winding, which may, for example, be carried out by connecting the pulse member not to earth, but to a suitable potentiometer of the battery. The connection between the two windings of the relays may then be dispensed with.

What we claim is:

- 45 Apparatus for registering pulses comprising a voltage source having two terminals, a pulsing member responsive to incoming sequential pulses and including a connecting element and first and second contacts alternately engaged by said element in response to an applied pulse, 50 said element being connected to one terminal of said source, a series of at least three relays each provided with a winding and first, second and third switches actuated thereby, each switch having a connecting arm and make and break contacts engaged thereby, means serially connecting the arms through the associated break contacts in the first switches of all relays in said series except the last thereof between one end of the winding of said last relay and the first contact of said pulsing member, the second contact of said pulsing member being connected 55 to one end of the winding of the first relay in said series, means serially connecting the arms through the associated break contacts of the second switches in all relays in said series except the first thereof between the other end of the winding of said first relay and the other terminal of 60 said source, means serially connecting the arms through the associated break contacts of the third switches in all relays in said series except the first and second thereof between the make contact of the second switch in said second relay and said one terminal of said source, the 65 winding of each of said relays except said first relay being connected between the break contact in the corresponding second switch and the make contact of the first switch associated with the preceding relay in the series, means 70 cross-coupling the make contacts of the second and third switches to the break contacts of the second and third

switches associated with all the relays in the series except the first and second thereof, and holding circuit means in conjunction with each relay in said series.
